Anton G. Sulak.
BY
James E. Sproll,
ATTORNEY

UNITED STATES PATENT OFFICE.

ANTON G. SULAK, OF SEATTLE, WASHINGTON.

PIANO.

Application filed August 1, 1923. Serial No. 654,966.

The present invention relates to structural improvements in pianos and in the redisposition of the several sound producing elements thereof in relation and with respect 5 to each other, whereby a sweeter, richer, mellower, more varied and expressive tone is obtained therefrom substantially equal to the tone obtained from the best and highest 10 grades of stringed instruments, which improved tone for pianos was heretofore and is unobtainable and unattainable from pianos now in use and in process of manufacture due primarily to the present mode of construction, combination, arrangement and 15 disposition and the sound producing elements thereof, causing and producing the objectionable, unavoidable and undesirable metallic sounds heretofore so common in pianos of all types and which seriously impairs 20 the tone thereof, but which have been substantially reduced to the irreducible minimum in pianos fabricated in accordance with the present invention.

With the above and other ends in view my 25 invention resides in disposing and locating the several bridges of the piano in a plane adjacent to and upon one side of the plane of contact or striking line of the action hammers on the strings thereof whereby the 30 vibrations set up in said strings are transferred directly through said bridges to the sounding board, where heretofore in pianos of all types and classes the bridges thereof were disposed and located at the ends of the 35 strings furthest removed from such plane of contact of the hammers with said strings, thus causing the vibrations set up in said strings to travel substantially the full length of the strings before reaching the bridges 40 causing loss in volume and producing the objectionable and undesirable metallic sounds due primarily and largely to the proximity and immediate nearness of the metallic string plate to the plane of contact 45 of the hammers with the strings which in pianos now in use and in process of construction is uniformly closer to said plane of contact than the said bridges.

The invention further resides in the provision 50 of a piano wherein the bridges thereof are disposed on the tuning pin side of the plane of contact of the hammers and adjacent thereto, where heretofore said bridges were disposed upon the opposite or hitch pin side of the said plane of contact and remotely therefrom which redisposition and rearrangement of parts of the present invention was found necessary and essential to produce and obtain the maximum resonance thereby amplifying the quality and 55 volume of tone of the piano.

The invention further resides in the provision of a piano wherein the several bridges thereof are disposed remotely from the hitch pins of said piano, to thereby reduce the pressure or tension of the strings on the said bridges, while also functioning to improve the quality and volume of tone of the piano, due to the greater distance between 60 the bridges and the hitch pins, thus allowing for greater vibration of the sounding board.

It is well known that in order to obtain the maximum tonal effects and results from stringed instruments such as violins, violas, 65 violoncellos and the like that the strings of such instruments must be played upon at a point adjacent to the bridges thereof and not at the finger boards. The vibrations set up in the strings of stringed instruments when played upon in close proximity to the bridges thereof are transmitted directly through the media of said bridges to the associated sounding boards thereof, thereby 70 producing the maximum quality and volume 75 of tone from said instruments. It is therefore the primary aim and object to provide a piano having the quality and volume of tone substantially equivalent to and possessed by the highest and best grades of 80 stringed instruments and in order to accomplish and attain these ends it has been found necessary and essential to embody the above principle in piano construction and dispose the bridges of said piano adjacent and in 85 close proximity to the plane of contact or striking line of the action hammers with or on the strings thereof, whereas in pianos now in use and under construction such 90 plane of contact or striking line of the hammers thereof are remote from the bridges, which principle is tantamount, identical and 95 equivalent to playing a stringed instrument at the finger board thereof, with a consequent loss of volume and quality of tone.

With the foregoing in view the invention

resides in the novel construction, combination, adaptation and arrangement of parts, as will hereinafter be more fully described and succinctly defined in the appended 5 claims.

Referring now to the accompanying drawings wherein is illustrated the specific form of the invention, as at present preferred:

Figure 1 is a view in elevation of a piano 10 string plate and associated mechanism fabricated in accordance with my invention.

Fig. 2 is a view in transverse section taken on a broken line 2—2 of Fig. 1.

Fig. 3 is an enlarged fragmentary view of 15 a portion of the treble bridge and string plate illustrating the method of mounting the treble octave strings thereon.

Fig. 4 is a similar view of a portion of the bass bridge illustrating the method of mounting the base octave strings thereon, and 20

Fig. 5 is an enlarged transverse section of 25 the treble bridge illustrating the mode of attaching the same to the sounding board and the method of mounting the strings upon said bridge.

In the drawings similar reference characters designate similar parts throughout the several views, the numeral 10 designates a metallic string or piano plate of any suitable 30 design rigidly secured by lag screws 11 to a wooden frame 12.

The wooden frame 12 comprises a laminated 35 top rail or pin block 13, a bottom rail 14 rigidly connected by side rails 15 and suitably reinforced by a plurality of brace members 16.

A sounding board 17 fabricated from suitable wood, such as pine, is rigidly secured upon the forward side of the wooden frame 40 12 having a plurality of openings or slots 18 formed therein to permit of the sounding board vibrations rippling off into the air, substantially as obtains in the violin and other stringed instruments. Similarly secured to the rear side of the wooden frame 12 in spaced relation to the sounding board 16 is a back board 19 of maple or other hard wood.

The numeral 20 designates the plane of 50 contact or striking line of the hammers 21 of the piano and disposed immediately above the plane or line 20 is an arcuate bridge 22, for the treble and center octaves of said piano, having the outer end thereof disposed 55 in close proximity to the plane 20 and having the inner end thereof curve upwardly therefrom. The bridge 22, is rigidly secured to the sounding board 17 by gluing the same thereon reinforced upon the rear side thereof 60 of by wood screws 23. Similarly disposed above the plane 20 in spaced relation thereto and in substantial prolongation and spaced endwise relation to the bridge 22 is a slightly higher arcuate bridge 24 for the 65 bass octaves of the piano, said bridge 24 is

rigidly secured to the sounding board 17 in a manner similar to that described for the bridge 22.

The upper portion 25 of the string plate 10 constitutes the tuning pin block plate, 70 which in conjunction with the laminated top rail 13 receive and threadably retain a plurality of tuning pins 26 upon which are wound the upper or outer ends of a plurality of treble octaves strings 27, a plurality of 75 center octaves strings 28 and a plurality of bass octaves strings 29. The treble and central octaves strings 27 and 28 extend downwardly from their associated pins 26 and pass over the bridge 22 and around bridge 80 points or pins 30, rigidly secured therein, and extend downwardly therefrom and pass around dead points or pins 31 rigidly secured in the metallic string plate 10 and thence downwardly around hitch pins 32 85 similarly secured in said plate and thence upwardly around the dead points 31, the bridge points 30 back to the tuning pins 26. The bass octaves strings 29 extend downwardly from their associated pins 26 and 90 pass over the bridge 24 and around bridge points or pins 33 rigidly secured therein and thence diagonally downward therefrom over the vibrating portions of the central octaves strings 28 and around dead points or pins 34 95 to hitch pins 35, to which they are fixedly secured.

The strings 27, 28 and 29 are adapted to be rigidly clamped to their respective bridges 100 22 and 24 by metallic strips 36 having longitudinally disposed arcuate inner faces and are adapted to be superposed upon and seat said strings within arcuate depressions 37 formed longitudinally in the outer faces of said bridges, to thereby establish and maintain a positive contact between said strings and said bridges. The strips 36 are fixedly secured to the bridges 22 and 24 by screws 38. The upper and lower edges of the bridges 22 and 24 are formed angularly, as 105 shown in Fig. 5, to provide distinct and positive edge portions upon which the strings 27, 28 and 29 are adapted to rest.

Woven between the non-vibrating portions 110 of the strings 27, 28 and 29, which portions lie between the tuning pins 26 and the bridges 22 and 24 and between the lower dead points 31 and 34 and the hitch pins 32 and 35, are a series of felt strips 39 designed 115 to prevent and deaden such vibrations as may be set up in said non-vibrating portions by the vibrating portions of the strings lying between the bridges 22 and 24 and the aforementioned dead points 31 and 34.

The sounding board 17 and the back board 125 19 in conjunction with the side rails 15 of the wooden frame 12 form a resonance compartment 40, wherein the air is substantially enclosed or confined, whereby the sonority and tone volume is materially intensified and 130

amplified, thus when the several piano strings are played upon vibrations are set up therein and are directly transmitted through the several bridges to the sounding board 17 and are condensed within the said resonance compartment 40 by the air confined or enclosed therein prior to rippling off into the outer air through the openings 18 and intensifying the free vibration of said sounding board. In this way and in this form of construction, dissipation of sound is effectually reduced, also the full value of the tonal properties of the piano is obtained and created and such properties reach the ear unimpeded, and likewise the maximum resonance, power, depth and volume is secured from the piano.

Manifestly in a piano having the several sound producing elements thereof disposed and located in the manner shown and described the vibratory waves set up in the strings, when played upon, are transmitted directly to the sounding board through the media of the bridges without loss of time and with the minimum of impedance, thereby enriching and mellowing the piano tone and rendering the same sweeter, more varied and expressive. Further, by having the vibratory portions of the strings disposed between the bridges and the hitch pins, as shown and described, the tension and pressure formerly imposed upon said strings is greatly relieved, thereby allowing the sounding board greater freedom to vibrate than heretofore obtained in pianos.

It is well known by those skilled in the art, that ten vibratory waves are set up in any string of a stringed instrument, when played upon, regardless of the length of the string, the length of the waves being determined by the length of the string, and the pitch of the tone of the string being determined by the length of the waves. I have therefore found it expedient in practice, in order to achieve the object and end sought, and as hereinbefore set forth, to establish the plane of contact of the action hammers with the strings at one vibratory wave length, or one tenth the length of the strings, from the bridges affixed to the sounding board.

While I have herein shown and described my invention with sufficient detail to enable those skilled in the art to understand the mode of construction and the principles involved, it is to be understood that there is no intentional limitation herein to the specific form and precise details of construction of the invention shown and described, except as expressly defined by the appended claims, and that various modifications of said construction may be resorted to without departing from the invention or the benefits derivable therefrom. I also desire it to be understood that certain features of the in-

vention herein shown and described may be employed in other combinations than those herein shown.

Having thus fully described my invention, what I claim as new and desire to secure by Letters Patent of the United States is:—

1. In a piano, the combination of the string plate, the strings, the action hammers, the sounding board, and a bridge affixed to said sounding board in close proximity throughout the length thereof to and upon the tuning pin side only of the plane of contact of said action hammers with said strings. 75

2. In a piano, the combination of the string plate, the strings, the action hammers, the sounding board, and a bridge affixed to said sounding board substantially midway of the vibratory portion thereof and upon the tuning pin side only of the plane of 85 contact of said action hammers with said strings. 80

3. In a piano, the combination of the string plate, the strings, the action hammers, the sounding board, and a bridge affixed to 90 said sounding board in transverse relation thereon and upon the tuning pin side only of the plane of contact of said action hammers with said strings. 95

4. In a piano, the combination of the string plate, the strings, the action hammers, with a sounding board curved outwardly in the general direction of the length of the same having the highest point of the curvature thereof substantially midway of the 100 length, and a bridge affixed to said sounding board at said highest point and upon the tuning pin side only of the plane of contact of said action hammers with said strings. 105

5. In combination with a piano, of a string plate having a vibration deadening ridge formed upon the hitch pin end thereof, a sounding board associated therewith, a bridge affixed to said sounding board, and strings attached at the ends thereof to the 110 tuning and hitch pin ends of said string plate and extending therebetween across said bridge and said vibration deadening ridge having the vibratory portions thereof extending between the said bridge and said 115 vibration deadening ridge. 110

6. In a piano, the combination of the string plate, the strings, the action hammers, the sounding board, and a string supporting bridge affixed to said sounding board at one 120 vibratory wave length of each of said strings from and upon one side only of the plane of contact of said action hammers with said strings. 120

7. In a piano, the combination of the string plate, the strings, the action hammers, the sounding board, and a string supporting bridge affixed to said sounding board upon the tuning pin side of and at approximately 125 one-tenth of the length of the vibratory por- 130

- tion of each of said strings from the plane of contact of said action hammers with said strings. 30
8. In combination with a piano, of a sounding board, a bridge for the treble and central octaves affixed to said sounding board, and a bridge for the bass octaves affixed to said sounding board in spaced endwise relation to said first named bridge. 35
- 10 9. In a piano, the combination of the string plate, the strings, the action hammers, the sounding board, and a plurality of bridges for the treble, central and bass octaves affixed to said sounding board in spaced endwise relation and upon the tuning pin side only of the plane of contact of said action hammers with said strings. 40
- 15 10. In a piano, in combination, a string plate having treble, central and bass octave strings attached thereto, action hammers associated with said strings, a sounding board associated with said string plate, a bridge for said treble and central octave strings, and a bridge for said bass octave strings, said bridges being affixed to said sounding board in spaced endwise relation and in substantial prolongation to each other and in close proximity throughout their length to the tuning pin side of the plane of contact of said action hammers with said strings. 45
- 20 11. In a piano, in combination, a frame, a resonator secured within said frame, a string plate secured to said frame, strings attached to said string plate, action hammers associated with said strings, and a string supporting bridge affixed to the forward wall of said resonator in close proximity to and upon the tuning pin side only of the plane of contact of said action hammers with said strings. 50
- 25 12. In a piano, in combination, a frame, a resonator secured within said frame, a string plate secured to said frame, strings attached to said string plate, action hammers associated with said strings, and a plurality of bridges for the treble, central and bass octaves affixed to the forward wall of said resonator in spaced endwise relation and in substantial prolongation to each other, said bridges being disposed upon the tuning pin side of and in close proximity to the plane of contact of said action hammers with said strings. 55

In testimony whereof I affix my signature.

ANTON G. SULAK.
